Primary Examiner — Mojtaba Tehrani

(57) **CLAIM**

The ornamental design for a grooving insert, as shown and described.

DESCRIPTION

1. Grooving Insert
- 1.1 : Perspective view;
- 1.2 : Side view;
- 1.3 : Side view;
- 1.4 : Top view;
- 1.5 : Bottom view;
- 1.6 : Side view;
- 1.7 : Side view;

1 Claim, 7 Drawing Sheets(56)
